UNITED STATES PATENT OFFICE.

DAVID PURVES, OF FERRO DENE, GREEN LANE, NORTH DULWICH, COUNTY OF SURREY, ENGLAND.

BOILER-FLUE.

SPECIFICATION forming part of Letters Patent No. 372,487, dated November 1, 1887.

Application filed October 23, 1886. Serial No. 217,033. (No model.) Patented in England March 23, 1885, No. 3,722.

To all whom it may concern:

Be it known that I, DAVID PURVES, of Ferro Dene, Green Lane, North Dulwich, county of Surrey, England, have invented a new and useful Improvement in Boiler-Flues, (for which I have obtained a patent in England, March 23, 1885, No. 3,722,) of which the following is a specification, reference being had to the annexed drawings, forming a part thereof, in which—

Figure 1 is a transverse section of a portion of a boiler-sheet, taken on line $x-x$ in Fig. 3. Fig. 2 is a transverse section of a portion of a boiler-sheet, taken on line $x-x$ in Fig. 3; and Fig. 3 is a transverse section of a boiler-flue, showing the projection of the circumferential ribs.

Similar letters of reference indicate corresponding parts in all the views.

The object of my invention is to provide a boiler-flue having strengthening-ribs formed integrally with the plates for strengthening the flues, to enable them to better withstand the steam-pressure, but so constructed as to give that required strength without the formation of cavities likely to gather injurious deposits of scale, and without the circumferential seams which are required when a flue is formed of a series of flanged hoops or is stiffened by separate channeled hoops.

The invention consists of a boiler-flue provided with a band or rib formed integrally therewith and in forming such rib upon the plate, substantially as hereinafter more fully set forth.

In carrying out my invention I roll in each plate of which the flue is formed ribs B, which project beyond the general plane of the plate, upon one side thereof, the plate being concaved

or channeled in the other side directly opposite the rib, and I make the rib radially thicker than the body of the plate. On section the ribs are, when finished, as shown by A in Fig. 1 or B in Fig. 2, at such distances apart as the strength required will admit. Between the ribs the flue is a plain cylinder. After the plates are bent into the required curved form, the adjoining ends of the plates are secured together by welding or riveting. The plates are preferably bent with the ribs on the concave surface. The thickened bands for the ribs are made on the plate before the plate is bent into cylindrical form; but the rolling of these thickened bands into ribs may be performed either before the plate is bent or after it is bent. When the ends of the plates are joined by riveting, the ribs will be finished before the plates are bent.

Having thus fully described my invention, I claim as new and desire to secure by Letters Patent—

1. In the manufacture of boiler-flues, the herein-described method of making the same, which consists in forming the plate with thickened bands on one side and channeling it on the opposite side, and then rolling the thickened bands into stiffened ribs, with the channel intact, substantially as set forth.

2. A boiler-flue formed of a plate having circumferential channeled stiffening-ribs formed upon the plate by rolling without intermediate circumferential seams, substantially as described.

DAVID PURVES.
